UNITED STATES PATENT OFFICE.

JOHN I. BERRY, OF WILLIAMSPORT, PENNSYLVANIA, ASSIGNOR TO GEORGE W. KLUMP, OF SAME PLACE.

METALLIC FASTENER FOR WOOD JOINTS.

SPECIFICATION forming part of Letters Patent No. 412,696, dated October 8, 1889.

Application filed October 10, 1888. Serial No. 287,774. (No model.)

To all whom it may concern:

Be it known that I, JOHN I. BERRY, a citizen of the United States, residing at Williamsport, in the county of Lycoming and State of Pennsylvania, have invented certain new and useful Improvements in Metallic Fasteners for Wood Joints; and I do hereby declare the following to be a full, clear, and exact description of the invention, which will enable others skilled in the art to which it appertains to make and use the same.

The invention which forms the subject of this specification, and which will be described presently, relates to a new and useful device for fastening together two adjoining pieces of wood, being particularly valuable when the use of nails or screws is not desirable, either from the unpleasant appearance to the eye of the heads of such nails or screws, or in cases when it is really impossible to make use of the same; and this invention is characterized by extreme simplicity and thorough effectiveness, at the same time being very economical and easy of insertion.

In order that others may understand my device, attention is invited to the accompanying drawings, which form a part of this specification, and in which—

Figure 1 is a perspective view of the preferable form of fastener; Fig. 2, a top elevation of the same; Fig. 3, a top view of the fastener, showing it when in position in two pieces of wood; Fig. 4, a modification in the form of the fastener; Fig. 5, a top elevation showing the connecting end straight instead of curved, as in Figs. 1, 2, 3, and 4.

In all of these figures the same parts are designated by identical letters of reference.

Before beginning the description of the form of my invention the material of the same will first be dealt with.

Although I do not wish to be limited to its use, I prefer to make the fasteners out of ordinary thin flat sheet iron or steel cut into long strips, varying anywhere from three-eighths to an inch or two in width, and these strips are again cut into shorter pieces of the right length for the fastener.

Instead of sheet iron or steel I could make use of tin or sheet-brass; but these latter materials are not so advantageous as the former

ones mentioned in being too soft and too expensive.

The preferable form A of my device is illustrated in Figs. 1, 2, and 3, and is of a general horseshoe shape, with the curved portion *a*, the straight parallel sides *b b*, and the turned-in ends *c c*. The curved portion *a* is not an indispensable element in this form, as it could be substituted by a perfectly-straight portion, as shown in Fig. 5, without affecting in any way the results accomplished by the fastener when in use.

The manner of using such a device as just described is as follows: Suppose it is desired to fasten the two pieces of wood *x* and *y* securely and rigidly together. The two pieces are first placed and held firmly together with the grain of the wood running parallel and in the same direction. The fastener is now placed on these ends edgewise, and with its sides parallel with the grain of the wood, so as to bridge over onto both, as shown in Fig. 3, and is then driven down into the ends, so that the upper portion of the whole device is flush with the top of both pieces. It is immaterial as to the nature and construction of the driving implement used for this purpose, and I do not wish to be limited to any in particular.

When the fastener is in position as shown in Fig. 3, it will be seen that the piece *x* is firmly held by means of the curved portion *a*, and that the piece *y* is held by means of the turned-in ends *c c*, so that it would be almost impossible to separate the two pieces. It might be advisable, though of course not absolutely necessary, to glue the two pieces together first before inserting the fastener; but this means, while possessing some advantages, is open to the objection of being more expensive and laborious.

In Fig. 4 is shown a modification in the form of my fastener. The peculiar feature in this modification is, that the ends or lugs *c c* are turned outwardly instead of inwardly, as in the other forms. This form might be very conveniently used in some instances where it would be impossible to make use of the preferred form of fastener, when the wood would be of a peculiar grain and demanded such.

When I have used the expression "horse-

shoe-shaped" to indicate the form of the fastener, I would have it understood that said expression is to convey the idea of the shape shown in the drawings, wherein the fastener 5 is represented as having straight sides parallel, or approximately so.

Having now described my invention, what I claim, and desire to secure by Letters Patent, is—

10 A metallic fastener made of thin flatsheet

metal of a general horseshoe shape, with straight parallel sides and with retaining ends or lugs *c c*, and adapted to be driven edgewise, substantially as set forth.

In testimony whereof I affix my signature in 15 presence of two witnesses.

JOHN I. BERRY.
